(57) **CLAIM**

The ornamental design for an ergonomic handle, as shown and described.

DESCRIPTION

FIG. 1 is a perspective view of one embodiment, according to the present invention;

FIG. 2 is a side elevational view of the embodiment thereof;

FIG. 3 is a bottom elevational view of the embodiment thereof;

FIG. 4 is a top elevational view of the embodiment thereof;

FIG. 5 is a front elevational view of the embodiment thereof;

FIG. 6 is a rear elevational view of the embodiment thereof;

FIG. 7 is a perspective view of an additional embodiment, according to the present invention;

FIG. 8 is a side elevational view of the additional embodiment thereof;

FIG. 9 is a bottom elevational view of the additional embodiment thereof;

FIG. 10 is a top elevational view of the additional embodiment thereof;

FIG. 11 is a front elevational view of the additional embodiment thereof; and,

FIG. 12 is a rear elevational view of the additional embodiment thereof.
